EDGE-FINISHING SEAM FOR PILE-FABRIC ARTICLES AND METHOD OF MAKING THE SAME

George W. Wesson, Bridgeport, Conn., assignor to The Singer Manufacturing Company, Elizabeth, N. J., a corporation of New Jersey

Application September 3, 1942, Serial No. 457,156

7 Claims. (CL. 112—262)

This invention relates to methods of sewing and seams for sewed articles.

An object of the invention is to provide an improved edge-finishing seam for pile-fabric articles, whereby the raw edges of the base-fabric of the articles are securely bound and the binding is neat and inconspicuous in appearance.

Another object of the invention is to provide an improved method of finishing the edges of pile-fabric articles, thereby to facilitate and speed production of the edge-finishing seams. Other and more specific objects of the invention will be apparent from the following description and claims.

The invention consists in the edge-finishing seam and the method of making the same as hereinafter described in connection with the accompanying drawings of a specific embodiment of the invention and in which:

Fig. 1 is a perspective view, partly in section of a rug edge with a binding strip attached thereto in accordance with the first step of the present method.

Fig. 2 is a perspective view of a portion of a rug edge finished in accordance with the present method.

Fig. 3 is an enlarged sectional view of the present rug-edge-finishing seam; the section being taken substantially on the line III—III of Fig. 2.

Fig. 4 is a plan view of part of a sewing machine by which the first part of the present method may be practiced.

Fig. 5 is a section on the line 5—5, Fig. 4, and Fig. 6 is a section on the line 6—6, Fig. 4, with the rug edge and binding strip in their relative positions for attachment by the reciprocating needles of the machine.

Fig. 7 is an enlarged perspective view showing a thread arrangement employed in the present invention.

Referring more specifically to Fig. 1 there is shown a portion of a pile fabric article having pile fibres 1 rising from one face of a woven base material 2 having a raw edge portion 3. A binding-strip 4 has a longitudinal edge portion 5 thereof secured substantially in edge-to-edge register and face-to-face contact with the pile-face of said article by means of a line or row of penetrant thread loop structures 6 positioned adjacent said registered edges and penetrating both binding strip 4 and base material 2. The thread loop structures 6 are keyed on the back face of the base material by thread structures 7 which in turn are keyed to the back face of the

base material by means of a second line or row of penetrant thread loop structures 8 penetrating only the base material 2, buried in the pile fibres 1 and positioned more remotely from the raw edge portion 3 than said first row of thread loop structures 6.

In a subsequent operation the binding strip is folded about the line of binding-strip penetrant thread-loops 6 and the raw edge portion 3 into engagement with the back face of the base material 2 so as to cover exposed parts of the thread structures 6, 7 and 8. The binding strip 4, in its folded position, is then secured to the base material 2 by any standard method but preferably by means of a row of lock stitches 9 as shown and described in my prior U. S. Patent No. 2,293,665, October 3, 1942.

Preferably, but not necessarily, the thread arrangement, as shown in Fig. 7, comprises two substantially parallel lines of thread loops 6 and 8, connected by a single thread 1 passed successively through said loops to lock them in the material penetrated by said loops.

It is evident from the description given above that the edge-finishing seam described above may be produced by a series of separate operations. However, the method of this invention may be more conveniently practiced by employing a sewing machine in part herein illustrated and more fully shown and described in my copending patent application Serial No. 457,155, filed herewith, and now matured into Patent No. 2,346,637, dated April 11, 1944.

For making the edge-finishing seam according to the present invention, a sewing machine having two endwise reciprocating needles 10 and 11 cooperating with a single rotary shuttle (not shown) disposed below bed-plate 12, may be provided with a presser-foot having adjacent tread portions 13 and 14 laterally spaced to provide therebetween a work-clearance slot 15. The presser-foot is yieldingly opposed to a four-motion feed-dog 16 operating through feed-slots in a throat-plate 17 to advance the work along the work-support. The shuttle rotates in a vertical plane transverse to the line of feed and functions to seize both of the thread loops presented by the two needles and to carry said thread-loops about a mass of under-thread. As the stitch-forming mechanism referred to is well known in the art, a detailed description thereof is deemed unessential to an understanding of the present invention.

A strip guide-tube may be provided having an L-shaped strip passageway with the vertical por-

tion 13 disposed to extend into the slot 15 and the horizontal portion 19 disposed beneath the tread portion 13 in advance of the needle 10, to guide the binding strip 4 into proper edge-register and face-contacting relation with the pile fabric article and to present them together in said relation to the needle 10 which may apply the thread loops 6 thereto.

The tread portion 14 of the presser-foot may be provided with a depending pile-dividing plow 20 in advance of the needle 11 to divide the pile fibres 1 as the material is fed through the machine and to cleanly bury the top portions of thread loop structures 8 in the pile fibres 1.

As the machine is provided with one rotary shuttle, the threads from the two needles are concatenated with the single bobbin thread to form a deep anchorage in the base fabric 2 for the tape-securing seam as well as a reinforcement for the edge of the pile-fabric article.

It is evident from the above description that the pile-fabric material is fed through the machine flatly, straightly and with the pile face up and thus does not require special handling which would impede production.

It will be obvious to those skilled in the art that the invention may, without departure from its essential attributes, be embodied in various specific forms other than those shown and described which latter are to be considered in all respects as illustrative of the invention and not restrictive, reference being had to the appended claims rather than to the foregoing description to indicate the scope of the invention.

Having thus set forth the nature of the invention, what I claim herein is:

1. In the method of finishing the raw edge of the base-fabric of a pile article, the steps including superimposing a longitudinal margin of a binding strip upon the pile face of the raw-edge margin of the base-fabric with the body of said strip disposed entirely at the base-fabric side of said raw edge; passing separate and substantially parallel rows of thread-loops through said base-fabric, a first of said rows of thread-loops penetrating the strip and base-fabric margins in proximity to the raw edge of the base-fabric, and a second of said rows of thread-loops being free of said strip and buried in the pile of the article at the side of said first row of thread-loops opposite the raw edge of the base-fabric; and anchoring the first of said rows of thread-loops to the second of said rows.

2. In the method of finishing the raw edge of the base-fabric of a pile article, the steps including superimposing a longitudinal margin of a binding strip upon the pile face of the raw-edge margin of the base-fabric with the bodies of said strip and base-fabric both disposed at the same side of said raw edge of the base-fabric; passing separate and substantially parallel rows of thread-loops through said base-fabric, a first of said rows of thread-loops penetrating the strip and base-fabric margins in proximity to the raw edge of the base-fabric, and a second of said rows of thread-loops being free of said strip and buried in the pile of the article at the side of said first row of thread-loops opposite the raw edge of the base-fabric; forming a furrow in said pile to receive said second row of thread-loops, and anchoring the first of said rows of thread-loops to the second of said rows.

3. The method of binding the margin of a body-fabric having top and bottom faces, comprising the steps of securing one edge of a bind-

ing strip to the top face of the body-fabric margin by a first stitching thread passed through the binding strip and the body-fabric; simultaneously passing a second stitching thread through only the body-fabric a substantially fixed distance from said first stitching thread on the side thereof which is remote from said body fabric margin; concatenating said first and second stitching threads on the side of the body-fabric opposite to the strip-face thereof; thereafter folding the binding strip around the seamed marginal edge of the body-fabric into engagement with the bottom face of said body-fabric; and securing said binding strip to said body fabric in said folded relation by a row of stitches more remote from said raw edges than said second stitching thread.

4. The method of applying a binding strip to the edge of a body-fabric having a pile face and a back face comprising the steps of superimposing one longitudinal marginal portion of the binding-strip upon one longitudinal marginal portion of the pile face with said portions in substantial edge-to-edge register; applying a row of thread-loops disposed substantially parallel and proximate to the registered edges and penetrating both binding strip and body fabric; applying an additional row of thread loops penetrating only the body fabric and disposed parallel to said registered edges and more remote therefrom than said proximate row; anchoring the thread-loops in said proximate row to those in the more remote row by thread means applied on the back face of the body fabric; folding said binding strip about the registered edges into engagement with the back face of the body-fabric to cover the stitched portion; and securing said binding strip to the back face of said body fabric.

5. The method of binding the raw edge of a rug of pile-fabric which consists in simultaneously presenting the rug edge and superposed edge of a binding strip to a sewing machine having two needles and a loop-taker complementary to both of said needles in the formation of stitches, with the rug face up and with the binding strip bent upwardly between the two needles so that only one of the needles penetrates both the strip and the rug to seam the two materials together; and in thereafter folding the unattached portion of the binding strip about said rug-edge and securing it to the back of the rug.

6. In a rug-edge-finishing seam, a rug-body comprising a woven base having a face and back with pile-fibres attached to said base and projecting from the face side of the latter, said base having a raw edge, a binding strip having an edge-portion in juxtaposition with said raw edge; a first stitching thread passed through both the binding strip and the rug-body adjacent said juxtaposed edges, a second stitching thread passed through the rug-body only and disposed on the side of said first stitching thread remote from said raw edge, a third thread disposed on the back of said rug-body in concatenation with said first and second threads, said binding strip being folded over said first stitching thread and about said raw edge into engagement with the back of the rug in covering relation to said third thread, and additional means securing the folded binding strip to the back of the rug.

7. In the method of finishing the raw edge of a base-fabric, the steps comprising superimposing a longitudinal margin of a binding-strip upon the top face of the raw edge margin of the base-fabric with the body of said strip disposed en-

tirely at the base-fabric side of said raw edge; passing separate and substantially parallel rows of thread loops through said base-fabric, a first of said rows of thread loops penetrating the strip and base-fabric margins in proximity to the raw edge of the base-fabric, and a second of said rows of thread loops being free of said strip and more remote from said raw edge; concatenating

an anchoring-thread with said rows of thread loops at the back face of said base-fabric; and thereafter folding said binding-strip about the raw edge of the base-fabric and securing said strip to said back face of the base-fabric in anchoring-thread covering relation.

GEORGE W. WESSON.
